UNITED STATES PATENT OFFICE

JAMES D. MALCOLMSON, OF NEW YORK, N. Y., ASSIGNOR TO ROBERT GAIR COMPANY,
OF NEW YORK, N. Y., A CORPORATION OF NEW YORK

TWO-PIECE CARTON SATCHEL

Application filed September 12, 1928. Serial No. 305,588.

The present invention relates to cartons, and has particular reference to an improvement in cartons made of paste-board, cell-board and the like, it being understood that the invention is not limited to these materials.

5 One of the main objects of the invention is to provide a simple, yet strong container for carrying therein weighty or bulky articles, such as bottles and the like.

10 Another important object of the invention resides in the ease of assembly of the improved container, the latter comprising only two coordinating members, the members being simple, blank forms, and requiring a minimum of labor and material in the development thereof.

15 A further object of the invention is to provide a carton of a simple type with means thereon whereby a handle grip may be formed, the grip being developed in the form of slotted openings in a pair of scored, vertical ended, opposing closure members, thereby to afford a convenient hand grip for portage.

20 Another object of the invention is to provide, a structure suitable for the carton purposes herein outlined, having the coacting parts thereof so constructed as to permit them to be shipped, in packed, large quantities in collapsed condition, and being easily and readily erectible for use, as required.

25 Still another object of the invention is to provide an improved carton structure, so arranged and designed that the weight of the load carried therein, will cause the coordinating members of the carton to become more snugly engaged together.

30 And still another object of the invention is to provide an improved carton structure comprising only two coordinating members, one of which functions as a carrier for such articles, as bottles, and has means provided therein to positively maintain such articles out of jarring contact with each other while 35 in the carton, thus lessening the breakage

hazard during portage, and further provide handle means for the carton.

Still other objects of the invention are to improve generally the simplicity and efficiency of such devices and to provide a device 50 or apparatus of this kind which is economical, durable and reliable in operation, and economical to manufacture.

The inventive features for the accomplishment of these and other objects are shown 55 herein in connection with an improved carton which, briefly stated, includes a carton, comprising an outer carton or casing forming member, formed from a single blank and being in the form of a square tube and readily 60 collapsible, said member having open ends; and an inner article carrying member, adapted to be inserted into the interior of said outer member through either open end, said inner member being formed, in one instance, from 65 an elongated blank member and readily foldable, said inner member, when inserted in said outer member, providing a closure for the lower of said open ends, and a second split closure for said upper open end, said first 70 closure having a dimension of a greater length than that of the corresponding dimension of the open end whereby a wedging action therebetween is obtained, the second closure comprising two flap-like portions, said flap- 75 like portions having associated therewith means provided with a slot adapted to receive the fingers of a hand, to form a handle grip, and means associated with said flap portions to maintain articles, placed in the 80 inner carton member, out of contact with each other, while in the carton.

Many of the features of this invention may be used without employing all of them, as some of those which are non-essential may be 85 omitted without departing from the spirit of the invention though such omission may to a greater or lesser extent affect the quality of the product. For the purpose of describing the invention, there are illustrated in the ac- 90

companying drawings the preferred forms of the device, in which drawings,

Fig. 1 is a perspective view of the erected inner container member, provided with handle gripping portions,

Fig. 2 is a perspective erected view of the outer container member,

Fig. 3 is an end view of the collapsed outer container shown in Fig. 2, ready to be packed for shipment,

Fig. 4 is an enlarged sectional view showing the load-carrying assembly of the carton, comprising the members shown in Figs. 1 and 2,

Fig. 5 is a developed blank of the inner carton member as disclosed in Fig. 1, showing the handle gripping means and the various scoring lines to permit folding thereof into carton form,

Fig. 6 is a sectional view of a modified form of carton, similar to that described in the foregoing figures, the handle or grip portion of the inner member being modified so as to function in a somewhat different manner, under load, than that described in the previous figures,

Fig. 7 is a sectional view of another modified form of carton, similar to that described in Fig. 6, the inner member being so modified as to maintain the articles therein separate,

Fig. 8 is a perspective erected view of the carton shown in Fig. 7,

Fig. 9 is a front elevation of the development shown in Fig. 10, the member portions being partially erected,

Fig. 10 is a development in plan of the inner carton member shown in Fig. 7.

Referring to the accompanying drawings, in which like characters of reference indicate the same parts in the different views, my device comprises two carton members, substantially rectangular in their coordinating dimensions, and preferably made of suitable straw-board, paste-board or, as in the present instance, in its preferred embodiment, of cell-board.

The latter material lends itself readily to the blanking, scoring and bending operations required to form the herein container, and at the same time is sufficiently strong to carry a load therein without rupture or collapse. It is understood, of course, that other materials may be used. The present container is especially adapted for carrying bottles of beverage, such as ginger ale, in any desired quantity. The carton is so designed that both the inner and outer carton-forming members may be folded flat for shipment to the distributor or retailer of bottled goods, and thereafter readily erectible into carton form for the purposes herein outlined.

Referring now to Fig. 2, an outer carton-forming member 1 is provided, which comprises a single piece of cell-board of suitable dimension, scored at points 2, 3, 4 and 5 in

the usual well known manner, to form corner bends. By means of a glued corner tape 6, or by stapling, or by any other desired securing means, the outer carton member 1 is thus formed into a four-walled member, without top or bottom. This member is collapsible across two of its corners 2 and 5 or 3 and 4, for shipment, as indicated in Fig. 3, which is an end view thereof, showing said container in collapsed flat shipping condition.

When thus collapsed, large quantities of these outer containers may be packed in one bundle and removed therefrom, for use as desired, with facility.

The inner carton-forming member 7, Figs. 1 and 5, is, also, formed of a suitable cell-board or similar material. As shown in Fig. 5, this member comprises an elongated blank substantially rectangular in form and embracing within its dimensions, across the narrow way at A, Fig. 5, the inside dimension of the outer carton 1. In its lengthwise dimension B, Fig. 5, it embraces within it, the bottom-forming section 8, the side walls 9, the top cover-forming sections 10, and extensions 11.

The extensions 11 meet at the center of the carton top as shown in Fig. 4. They are, further, provided with hand slots 12 therein, and when the carton is in erected and assembled position, the hinged, scored and slotted end extensions 11 stand vertically from the carton top. In this position the hand slots 12 register, thereby forming a joint gripping or handle means whereby to carry the carton when in assembled and loaded condition.

The various panels or sections of the blank 7, Fig. 5, are scored at points *a* which correspond to the bending lines *a'*, Fig. 1, thereby to form a rectangular inner liner closed on all sides which are positioned in one plane, bottom and top, but open at opposite ends in a plane transversely to the first mentioned plane as shown. Therefore, it will be seen that the inner container-forming member, with the carrying grip thereon, is formed with a single wrap of a length of suitable material, scored as mentioned to snugly fit the interior of the outer container 1, when the latter is open in carton-forming position.

Owing to the structure of the inner carton member 7, and being of a single length of material, it may be folded on any of its score lines. If desired, it may be left flat, in blank form, as shown in Fig. 5, so that it may be shipped in bundles, together with bundles of the outer carton-forming members. Thus, a carton may be formed by merely folding the inner carton member at the scoring lines *a*, Fig. 1, and opening the outer carton member 1, as indicated in Fig. 2, and then assembling the inner member 7 within the outer member 1 in position, as shown in Fig. 4. The top or lid-handle portions 10 and 11 of the inner carton member may then be joined, the pack-

age or bottles inserted within the assembled container, the grip portions 12 being brought together as in Fig. 4, and the package is then ready for portage, tied or untied, as desired.

5 In addition to the foregoing, another modification may be also used and this is outlined in the sectional view, Fig. 6, which is a view on a reduced scale showing the outer and inner members in longitudinal section and 10 showing their operative engaging positions.

In the construction shown in Fig. 6, the outer carton 1 is identical with that as shown and described for Fig. 2 and, in effect, the inner carton-forming member 7 while slightly 15 modified, is also of a similar construction. The modification resides in the fact that the upper handle or grip portions 11 are provided each with an extended double intermediate flap 10' which is scored at points *c* between 20 the horizontal panels 10 and the vertical grip forming members 11 instead of immediately joining and being scored off of flaps 10. The portions 10' are connected as shown, by staples 13 to the extended grip portion 11. The 25 members 10' are so designed relative to the height of the inner member that bottles 14 placed in the latter are effectively separated, the members 10' 11 acting as a partition between the bottles 14, and thus preventing 30 jarring contact between the latter during portage.

Thus the added members 10' may be deflected or extended downwardly, when the members 11 are formed into grip portions, as 35 described above. There is, moreover, obtained a wedging or outward thrusting toggle action when the package is loaded and lifted by the grips 12, which tends to cause the upper ends of the inner carton 7 to expand outwardly against the upper open ends 40 of the carton 1. The result is that the inner carton 7 is tightly wedged against the outer carton 1, prevents undesirable movement, and firmly holds the two carton members in 45 assembled position, and the bottles 14 out of contact with each other.

As an added means for causing intimate wedging and engaging action between the inner and outer carton members in either of 50 the forms described for Figs. 1 or 6, the bottom panel 8 in its outer dimension D, Fig. 6, may be laid in somewhat larger dimension than the corresponding inner width of the bottom of the outer container 1. Thus, when 55 the inner member 7 is in operative position within the member 1, the bottom 8 is caused to wedge tightly within the confines of the member 1. Accordingly, as shown in the present described box in Fig. 6, the top or 60 cover portion comprising the parts 10, 10', and the bottom 8, are caused to tightly wedge, when in operative position and loaded, and to expand against the confining wall of member 1, in a tight friction engagement.

65 If desired, the inner and outer carton mem-

bers may be glued together on assembly, the outer faces of the sides 9 of both forms of inner carton members 7 may be spotted with a suitable adhesive, as silicate of soda, when erecting, so that they will be caused to become 70 gummed to the inner surfaces of the coacting outer carton member which are in contact with the walls of the inner carton-forming member 7.

In Figs. 7-10 inclusive, there is shown a 75 modified type of carton, constructed along the lines of the carton shown in Fig. 6. As in the other types, the outer carton member 1 houses the inner member, denoted generally by 15 in Fig. 7 and 8. The inner member comprises a 80 pair of rectangular blanks 16, 17 secured by staples 18. Each blank includes five panels, separated by score lines *b*, whereby the member 15 is assembled in erected form, as in Figs. 7 and 8, since the panels can be bent along 85 lines *b*. The general construction of this modification is similar to the forms shown in Figs. 4 and 6, except for the difference to be noted hereinafter.

In Fig. 10, the inner member 15 is shown 90 in developed form, viewed from blank 16. A panel 19 stapled to a panel 20, both slotted as at 21 for gripping purposes, form a vertical partitioning means in the inner member 15, and corresponds to the members 11 in Fig. 6. 95 Panels 22, 24, 25, 26, separated from each other by score lines *b* and connected to panel 19, are bent into erected position as shown in Fig. 9. Panels 23, 27, 28, 29, connected to panel 20, are likewise bent along the lines *b* 100 into erected position.

When in erected position, the entire inner member 15 is inserted into an open end of the outer member 1, as shown in Figs. 7 and 8. The panels 23, 22 form the bottom end closure 105 of the complete carton; panels 27, 24 form reinforcing walls; panels 28, 25 provide the top end closure of the carton; while, panels 29, 26 form flaps and means to maintain the bottles 30 in non-jarring position.

As shown in Fig. 8, the carton is gripped at 21, when the bottles 30 are packed into the compartments F, G formed by the panels referred to above. As in Fig. 6, the panels 22, 23 may be of such width as to enable the 110 bottom closure to wedge against the walls of the outer carton. It should be noted that, as in Fig. 6, the panels 27, 24 are forced against the walls of the outer member 1, due to the toggle-like action of the vertical partition 115 member 19, 20, when carried at 21.

As described above for the type shown in Figs. 1-6 inclusive, it is only necessary to ship the blanks in collapsed condition. The blanks 16, 17 of the inner member may be 120 stapled and shipped as shown in Fig. 10. When ready for use, the outer member 1 is erected, as in Fig. 2, and the inner member 125 folded, as shown in Fig. 9. The folded inner member is then inserted into the erected outer 130

member 1, and bottles 30 inserted into compartments F, G and the flaps 29, 26 are bent into position in contact with the vertical partition member 20, 19.

5 The fingers of the carrier may then be placed in the registering apertures 21 of the panels 19, 20, and the carton carried with facility. Irregardless of the amount of jarring given to the carton during portage, the 10 bottles are maintained separate. The carton is compact, the flaps 29, 26 snugly retained, and the bottles are removed from their respective compartments with facility.

It will thus be seen that I have designed 15 and developed a novel carton comprising a pair of simple, rectangular blank members, having coordinating carton dimensions so that one fits within the other snugly, and which carton is easy and economical to man- 20 ufacture, readily shipped to the consumer for use and assembly, and comprises a unitary, novel, and rigid construction, in which the articles carried do not contact with one another during portage.

25 The foregoing detailed description has been given for clearness of understanding. Hence, no unnecessary limitations should be understood. Further, the appended claims should be construed as broadly as permissible in view of the prior art, since many and various changes may be made without departing from the scope of the invention as defined in the broader claims.

What I desire to protect and secure by Letters Patent is:

1. A carton, of the class described, comprising an outer carton-forming member, formed from a single blank and being readily collapsible, said member having open 40 ends, and an inner carton-forming member, adapted to be inserted into the interior of said outer member through either open end, said inner member being formed from an elongated blank and being readily foldable, 45 said inner member, when inserted into said outer member, including a closure means for one of said open ends, and a second closure means for said other open end, said first closure means having a dimension of a 50 greater length than that of the corresponding dimension of the open end whereby a wedging action therebetween is obtained, the second closure means comprising two flap-like portions, and a handle means associated 55 with one of said closure means.

2. In a carton, an outer closure member, having open ends, an inner carrier member, adapted to house bottles therein, said inner member including a pair of portions to close 60 said open ends, one of said closure portions comprising a pair of hinged flaps, and a handle means for said carrier member, said handle means being further adapted to maintain said bottles in non-contacting position.

65 3. In a carton, as defined in claim 2, said

handle means comprising a pair of contacting, slotted portions, each of said portions being integral with one of said flaps, and the planes of said portions being substantially normal to the planes of the remainder of the flaps when in operative carrying position. 70

4. A carton of the class described, comprising an outer carton-forming member, and an inner carton-forming member adapted to house bottles, said inner member adapted to be inserted into the interior of said outer member, said inner member being formed from an elongated single blank and readily foldable, said inner member when folded including a pair of closures, one of the closures comprising two flap-like portions, each of which portions is provided with a slot adapted to receive the fingers of a hand, the remainder of each portion being substantially normal to that of the slot portions and so designed that when the slot portions are brought into contact with each other, said bottles are maintained in non-contacting position. 80

5. A carton, of the class described, comprising an outer carton-forming member, said member having open ends, and an inner carton-forming member, adapted to be inserted into the interior of said outer member through either open end, said inner member being formed from an elongated blank and when inserted in said outer member, including a closure for one of said open ends, a second closure for said other open end, the second closure member including 100 two flap-like portions, each of which portions is provided with a slot adapted to receive the fingers of a hand, the remainder of each portion and said closures being so designed that when the slot portions are brought into contact with each other and moved away from carton interior, the sides of the inner member are wedged tightly against the walls of the outer member. 105

6. In a carton an outer member, an inner member and one or more outwardly and inwardly extending parts on said inner member, integral therewith, said outwardly extending parts to form a handle for said carton and said inwardly extending parts to form a partition in said inner member, whereby to maintain articles placed therein in non-contacting position. 110

7. A carton comprising an outer member, an inner member telescoping therein, a handle part on said inner member, a portion of said handle part extending into the interior of said inner member and providing a partition therein. 115

8. In a carton an outer member and an inner member, to be slidably inserted thereinto, said outer member having thereon four closed sides and being open at the upper and lower ends thereof, said inner member having thereon two parallel closed sides, two 120

open sides and closures at the top and bottom thereof, one or more of said closures being initially wider than the corresponding open end of said outer member, whereby said inner member is wedged into position in said outer member.

Signed at New York in the county of New York and State of New York this 5th day of September, A. D. 1928.

10 JAMES D. MALCOLMSON.
